UNITED STATES PATENT OFFICE.

HENRY E. JOHNSON, OF DONNYBROOK, NORTH DAKOTA.

ELECTRIC-LIGHT-CORD REEL.

1,361,465.

Specification of Letters Patent.

Patented Dec. 7, 1920.

Application filed April 19, 1918. Serial No. 229,565.

To all whom it may concern:

Be it known that I, HENRY E. JOHNSON, a citizen of the United States, residing at Donnybrook, in the county of Ward, State 5 of North Dakota, have invented a new and useful Electric-Light-Cord Reel; and I do hereby declare the following to be a full, clear, and exact description of the invention, such as will enable others skilled in 10 the art to which it appertains to make and use the same.

This invention relates to an improved electric light cord reel, and an object of the invention is to provide a simple and 15 improved and practical device of this kind, which may be manufactured for a small cost and sold at a reasonable profit.

Heretofore the cord reel for electric lights, the cord is wound on the reel from 20 one end only, and this requires that the current be maintained by means of frictional contact between members. In other words the wire carrying the electric current to the bulb is required to be connected in 25 some suitable manner to the shaft on which the reel rotates, and then the hub of the wheel must remain in contact with the shaft to carry the current, and the cord carrying the bulb must necessarily be connected to 30 the reel, so as to carry the current.

The present invention aims to eliminate these disadvantages, by having the electric cord to the bulb unbroken, and to provide an improved reel, for reeling the cord from 35 the center toward both ends. By this arrangement the electric light may be raised more rapidly and avoids the impractical frictional means, to maintain the circuit.

In practical fields the details of construction 40 may necessitate alterations falling within the scope of what is claimed.

The invention comprises further features and combination of parts as hereinafter set forth, shown in the drawings and claimed.

45 In the drawings:—

Figure 1 is a view in side elevation of the improved reeling or winding device as applied to an electric light cord suspended from the ceiling.

50 Fig. 2 is a sectional view through the same, showing the reel in section and also the spring means.

Fig. 3 is a sectional view through the casing, showing the reeling and spring 55 means in elevation therein.

Fig. 4 is a sectional view on line 4—4 of Fig. 3.

Fig. 5 is a detail sectional view on line 5—5 of Fig. 3, looking in the direction of the arrow.

Referring more especially to the drawings 60 1 designates a casing which may be any suitable shape or construction, preferably spherical, and preferably consisting of two sections 2 and 3, one telescopically fitting the 65 other and being secured by suitable screws 4. One section 2 of the casing has a bearing 5 for the shaft 6. The other section 3 has a bearing 7 in which the other end of the shaft 6 is secured by the pin 8. A suitable 70 drum 9 is mounted revolubly on said shaft and the body of the drum has a laterally extending eye 10. The drum has circular flanges or disks 11 and 12 at both ends. The disk or flange 11 has a laterally extending 75 pin 13, and connected to said pin is one end of the wound tensioned spring 14, the other end of which is secured by a screw 15 to the projection 16 of the section 2 of the casing. It is to be noted that the bearing 5 is formed 80 in the projection 16. The lower part of the section 2 of the casing has a flanged opening 17 and the upper part of the section 3 has a flanged opening 18. The electric light cord passes through the casing and through 85 the openings 17 and 18, and through the eye 10 of the body of the drum. The circular flange or disk 12 has an exterior hub 19, which is chambered out as shown at 20. The shaft 6 where it passes through the chamber 90 20 is provided with diametrically opposite notches 21, and pivoted at 22 in the chamber 20 are pawls 23 provided with lugs 24, adapted to engage the diametrically opposite notches 21. The spring 14 is normally 95 wound, and the spring by being normally wound will hold the electric light cord normally wound on the drum or reel, from the middle toward both ends, and when the cord is entirely wound onto the drum the 100 electric light bulb 25 is adjacent the opening 17, and the opening 18 is adjacent the hanger or cord fixture 26 of the ceiling. It is to be noted that when it is desired that the bulb be lowered, a pull is imparted on the bulb, 105 in which case the cord will unreel from the drum. When the drum is rotating rapidly against the action of the spring 14, the pawls 23 will be thrown outwardly centrifugally, to release the drum. However, by virtue of 110

the pawls 23 the electric light bulb may be held in different adjusted or extended positions. In case the cord becomes entirely unwound, it is to be noted that a sudden pull on 5 the cord will so agitate the drum as to throw the pawls 23 outwardly to release the drum, to allow the cord to re-reel. This agitation of the drum is accomplished, since the eye 10 is placed on the side of the body of the 15 drum, then it will be seen that by holding the casing and agitating the cord up and down the drum may be agitated to release the pawls. However, should the pawls bind, in fact will not freely act or respond to the 20 centrifugal force, some suitable tool (not shown) may be inserted through one or the other of the openings 27, to move the pawls 23, so that the spring may rotate the drum and reel the electric light cord.

20 The invention having been set forth what is claimed as new and useful is:—

A reel fixture for electric light cords, said fixture comprising a reel having therein a shaft, axially aligned bearings or bosses for 25 supporting said reel and shaft, semi-spheri-

cal members on the concaved sides of which the bosses are integrally formed and centrally disposed, a spiral spring surrounding one of the bosses and having one of its ends secured to the boss and its other end secured to the reel, a cord oppositely wound on the reel, said reel being disposed in a horizontal plane, the connection between the semi-spherical member being in a vertical plane at a right angle to the reel shaft, outwardly extending hollow extensions carried by the semi-spherical members, and extending in opposite directions through which the ends of the cords feed, said shaft being secured in the bearing of the boss opposite the 40 spring engaged boss and ratchet and pawl means for holding the reel in any position against the action of the spiral spring.

In testimony whereof I have signed my name to this specification in the presence of 45 two subscribing witnesses.

HENRY E. JOHNSON.
